UNITED STATES PATENT OFFICE.

FREDRICK ZENKER, OF HIGHLAND PARK, MICHIGAN, ASSIGNOR TO SQUARE D COMPANY, OF DETROIT, MICHIGAN, A CORPORATION OF MICHIGAN.

QUICK-BREAK DOUBLE-THROW SWITCH.

1,400,400.

Specification of Letters Patent.

Patented Dec. 13, 1921.

Application filed June 1, 1918. Serial No. 237,718.

To all whom it may concern:

Be it known that I, FREDRICK ZENKER, a subject of the Emperor of Germany, residing at Highland Park, in the county of Wayne and State of Michigan, have invented certain new and useful Improvements in Quick-Break Double-Throw Switches, of which the following is a specification.

My invention relates to double throw switches of the quick break type, one of the objects of the invention being to provide an inclosed switch which may be operated by an external handle or operating member and is adapted to have a quick break at either of its extreme positions.

A further object of the invention is to simplify the construction of quick break double throw switches.

A further object of the invention is to design a quick break double throw switch in such a manner that a very rugged structure results.

A further object of this invention is to so arrange the movable and stationary contacts that an intermediate or neutral position may be secured.

One of the many possible forms of the invention is shown in the accompanying drawings, in which—

Figure 1 is a perspective view of the quick break double throw switch; and

Fig. 2 is a medial sectional view of the double throw switch mechanism.

Referring to Fig. 1 of the drawings, it will be seen that the switch is inclosed in a casing 1 having the usual hinged cover 2 and is provided with an operating member or crank 3. Such crank 3 is rigidly connected, and in the example shown, integrally connected with an internal-operating member 4. The member 4, it will be seen, is pivoted in the main or body portion of the casing at either side and approximately central thereof. This member 4 is adapted to impart its motion to the switch blades 5 through the medium of an operating lever 6 pivotally connected at 7 to a yoke 8. The yoke 8, it will be seen from reference to both Figs. 1 and 2, has a sliding connection through the slotted portion 9 with the cross heads 10. Such cross heads 10 are provided at their outer portions with insulating bushings 11 and clamping members 12 fastening such cross heads to the switch blades 5 as clearly shown at the upper right of Fig. 1. Upon reference to Fig. 2

it will be seen that the cross heads 10 are also yieldingly connected to the yoke member 8 by means of springs 13 which engage the cross head between the two arms 14—14 of the yoke member and at the other end are fastened to pins or bolts 15 which are slidably carried in a slot 16 in the yoke 8. The object of this slot 16 is to provide for sliding motion of the pins 15 in reference to the yoke 8 when the upper portion of the slot 9 engages one of the cross heads 10, whereby the springs 13 are not placed under compressive strain.

From reference to Fig. 2 it will be seen that the two arms or blades 5 are integral and form a widened V, pivoted at the base of the V at 18 to a central contact 19. In the example shown, two such blades and two such central contacts are illustrated. Contacts 20 coöperating with the blades 5 are provided at the outer portion of the insulating base 21.

The operation of this device is as follows: When the operating crank 3 is moved toward one limit of motion the pivoted lever 6 is rocked over in such direction and one of the shoulders 22 thereof engages a pin or stud 23 upon the operating member 8. This causes the operating member 8 to slide along the cross heads 10 until the upper portion of the slot of one of such members engages one of the cross heads and forces it down and the attached blades into engagement with the stationary contacts. Now if the operating member 4 is moved in the opposite direction, the frictional engagement between the stationary spring contacts 20 and the blades 5 will resist the withdrawal of the blades 5. This will cause the lever 6 to move over and engage the other pin 23 through the medium of its shoulder 22 and will thereafter cause the yoke 8 to slide along the cross heads 10 until the lower portion of the slotted part positively engages the cross head and thereby withdraws the blades 5 from engagement with the contacts 20. As soon as the frictional engagement between the blades 5 and the contacts 20 diminish to such a point that the spring 13, which is elongated during this process, can overcome such resistance, the blades 5 are suddenly withdrawn from final engagement with the contacts 20. This obviously causes a quick break.

It will be seen from a reference to the two figures in the drawing that both sides of the

switch mechanism are identical, or, in other words, the two portions on either side of the center plane are symmetrical and operate in identically the same manner, and therefore a 5 description of one side will obviously be sufficient.

From the above description it will readily be seen that applicant has provided a double throw switch in which the operating crank 10 3 through the medium of the operating member 4 and interposed mechanism has positive engagement with the blades 5 to positively force such blades into contact with the fixed contacts. It will also be seen 15 that such operating crank 3 has positive engagement with the blades 5 through the interposed mechanism to positively withdraw the blades 5 from the stationary contacts. It will further be noted that spring 20 mechanism is provided whereby when the blades have become positively withdrawn to a certain extent from the fixed contacts, quick break or spring snap is secured.

The above detailed description and drawings are to be interpreted in an illustrative manner and not in a limiting sense, as this is only one of the many possible forms that applicant's invention may take, and, therefore, such invention is to be limited only as 30 defined by the following claims.

Having thus described the invention what is claimed as new and desired to secure by Letters Patent of the United States is:

1. A quick break double throw switch 35 comprising stationary and coöperating movable contacts, means for operating said movable contacts and causing a quick break, including a yoke supported by the movable contacts and a lever pivoted thereon.

40 2. A quick break double throw switch comprising stationary and coöperating movable contacts, means for operating said movable contacts and causing a quick break, including a yoke supported by the movable 45 contacts and a lever pivoted thereon and loosely connected to said yoke.

3. A quick break double throw switch 50 comprising stationary and coöperating movable contacts, means for operating said movable contacts and causing a quick break, including a yoke and lever pivoted thereon, said lever being provided with shoulders and coöperating pins on said yoke.

4. A quick break double throw switch 55 comprising stationary and coöperating movable contacts, means for operating said movable contacts and causing a quick break, including a yoke and a lever pivoted thereon and provided with shoulders and coöperating pins on said yoke, and only one pin and shoulder adapted to coöperate at one time.

5. A quick break double throw switch 60 comprising stationary and coöperating movable contacts, said movable contacts comprising V-shaped blades and connecting

cross heads, an operating member, and means for securing a quick break, including a member adapted to slide upon said cross heads having positive and yielding connections with the latter and a lost motion connection with said operating member. 70

6. A quick break double throw switch comprising stationary and coöperating movable contacts, said movable contacts comprising V-shaped blades and connecting 75 cross heads, means for securing a quick break, including a yoke, said yoke having slots therein through which said cross heads pass and having both yielding and positive engagement with said cross heads, whereby 80 a quick break is secured, and an operating member pivoted to said yoke but being capable of lost motion with respect thereto.

7. A quick break double throw switch comprising stationary and coöperating movable contacts, said movable contacts comprising V-shaped blades and connecting cross heads, means for securing a quick break, including a yoke, said yoke having slots therein through which said cross heads 90 pass, and springs connected to said cross heads and yoke, whereby said yoke has both positive and yielding connections with said cross heads, and an operating member having a lost motion connection with said yoke. 95

8. A quick break double throw switch comprising a plurality of stationary and movable contacts, cross heads connecting said movable contacts, a yoke having slotted arms engaging the cross heads and adapted to contact with the cross heads at the upper and lower ends of the slots, springs connecting said cross heads and yoke, and lost motion means for operating said yoke. 100

9. A quick break double throw switch 105 comprising a plurality of stationary and movable contacts, cross heads connecting said movable contacts, a yoke having arms provided with slots engaging the cross heads and adapted to contact with the cross heads 110 at the upper and lower ends of the slots, springs connecting said cross heads and yoke, and means for operating said yoke, including a pivoted lever which is capable of lost motion with respect to said yoke. 115

10. A quick break double throw switch comprising a plurality of stationary and movable contacts, cross heads connecting said movable contacts, a yoke having arms provided with slots engaging the cross heads and adapted to contact with the cross heads at the upper and lower ends of the slots, springs connecting said cross heads and yoke, and means for operating said yoke, said means including a pivoted lever provided with shoulders and coöperating pins 120 on said yoke. 125

11. A quick break double throw switch comprising a plurality of stationary and movable contacts, cross heads connecting 130

- said movable contacts, a yoke having arms provided with slots engaging the cross heads and adapted to contact with the cross heads at the upper end lower ends of the slots, 5 springs connecting said cross heads and yoke, and means for operating said yoke, said means including a rock arm, and a co-operating forked lever pivoted to said yoke.
12. A quick break double throw switch 10 comprising a plurality of stationary and movable contacts, cross heads connecting said movable contacts, a yoke having arms provided with slots engaging the cross heads and adapted to contact with the cross heads 15 at the upper and lower ends of the slots, springs connecting said cross heads and yoke, and means for operating said yoke, said means including an operating member and a co-operating forked pivoted lever provided 20 with shoulders and co-operating pins upon said yoke.
13. A quick break double throw switch 25 comprising a plurality of V shaped centrally pivoted movable contacts, sets of fixed contacts co-operating with the ends of the movable contacts, a crosshead insulatively interconnecting the movable contacts at each end of the V, and means for operating such movable contacts comprising a yoke loosely 30 coupled with the crossheads and a spring positively connected to each of the crossheads, and loosely connected to the yoke.
14. A quick break double throw switch 35 comprising a plurality of V shaped centrally pivoted movable contacts, sets of fixed contacts co-operating with the ends of the movable contacts, a crosshead insulatively interconnecting the movable contacts at each end of the V, and means for operating such movable contacts comprising a yoke loosely 40 coupled with the crossheads and a spring positively connected to each of the crossheads, and loosely connected to the yoke, said yoke being V shaped and the center of the V shaped yoke being remote from the 45 central pivot of the blades.
15. A quick break double throw switch comprising a plurality of stationary and movable contacts and cross heads connecting said movable contacts, an operating member, 50 a yoke co-operating with said operating member and cross heads and having a lost motion connection with both the cross head and the operating member, and having a resilient connection with said cross heads, 55 whereby a quick break is secured.
16. A quick break double throw switch comprising a plurality of stationary and movable V-shaped contacts, cross heads connecting said movable contacts, an operating 60 member, interposed means between said operating member and said cross heads for loosely connecting both the operating member and cross heads whereby the movable contacts are both positively and yieldingly 65 operated by the operating member in unison, and whereby the cross heads are also resiliently coupled with the said means.

FREDRICK ZENKER.
